AIR CONDITIONING UNIT FOR AUTOMOTIVE VEHICLES Harold E. Kunkel, 15570 Charles R. St.,
East Detroit, Mich.

Filed Aug. 4, 1965, Ser. No. 86,439

Term of Patent 14 years

(Cl. D14—6)

FIG. 1 is a perspective view of an air conditioning unit for an automotive vehicle;

FIG. 2 is a plan view thereof;

FIG. 3 is a front elevational view thereof; and

FIG. 4 is a side elevational view thereof.

The dominant features of the new design are shown in solid lines in the drawing.

I claim:

The ornamental design for an air conditioning unit for automotive vehicles, as shown and described.
